UNITED STATES PATENT OFFICE.

FRANK DAVID ELY, OF TIENSIN, CHINA.

FIREARM CONTROL.

1,329,230.

Specification of Letters Patent. Patented Jan. 27, 1920.

Application filed April 14, 1917. Serial No. 162,215.

To all whom it may concern:

Be it known that I, FRANK DAVID ELY, a citizen of the United States, and a resident of Tientsin, China, have invented a new and Improved Firearm Control, of which the following is a full, clear, and exact description.

My invention relates to fire-arm controls, and has reference more particularly to the indicator of the control. The invention constitutes an improvement over my patent issued January 5, 1909 under the number of 908,982.

An object of the invention is to provide a direct-reading scale with means for throwing the control into and out of operation by a simple manipulation of the indicator.

Another object of the invention is to provide a control which locks automatically at 20 a predetermined point of the scale.

With the above and other objects in view, the nature of which will more fully appear as the description proceeds, the invention consists in the novel construction, combination and arrangement of parts as herein 25 fully described, illustrated and claimed.

In the accompanying drawings, forming part of the application, similar characters of reference indicate corresponding parts 30 in all the views.

Figure 1 is a side elevation of a fire arm provided with an embodiment of my invention, part of the fire arm being broken out to show some features of the control and 35 their relation to the indicator;

Fig. 2 is a longitudinal cross section on line 2—2, Fig. 1;

Fig. 3 is an edge elevation on line 3—3, Fig. 1;

Fig. 4 is a face view of the setting block;

Fig. 5 is an elevation of the trigger and the operating mechanism of the fire control seen from the side opposite that shown in Fig. 1.

Fig. 6 is an enlarged perspective view of the block of the control; and

Fig. 7 is a side view of the pendulum.

Referring to the drawings, 5 is a pendulum of the control suspended from a pin 4 mounted in the sear and having a transverse tongue 6 at the bottom thereof and a pin 7 depending from the tongue, the pin engaging the slot 25 of the movable block 8 and the tongue adapted to register with 50 the transverse groove 12 of the said block. 55 The block 8 is guided by the groove 9, the

forward end of which curves downwardly for a purpose hereinafter set forth. The displacement of the block is controlled by an arm 10 the pivot of which is constrained 60 to move with the indicator arm 11. The firing of the arm is controlled by the register of the tongue 6 of the pendulum with the recess 12 in the block. The above structure is old and is shown in my patent referred to.

The indicator arm 11 has a pin 13 at the free end thereof and is so mounted on the side face of the fire arm that it may be depressed toward the face. The pin 13 travels 70 in an under-cut of a scale frame 14 secured to the said face of the fire arm. At the upper end of the under-cut for the pin, the frame 14 presents a notch 15 for receiving the pin and thereby lock the indicator lever 75 in that position which is marked on the scale frame "Off." It will be seen that when the indicator arm 11 is brought into that position the block 8, owing to the downwardly curved end of the slot 9, has dropped 80 down away from the pendulum so as not to interfere with its displacement and, therefore, with the firing of the arm, or rifle. This position of the indicating lever throws the control off from the arm and 85 permits the use of the arm in any ordinary way.

A screw 16 is revolvably mounted in the frame 14 to move a setting block 17 along the under-cut of the frame. The setting 90 block has an extension 18 projecting or extending into the under-cut provided with an elongated notch 19 for receiving the pin 13 of the indicator arm 11. The yielding properties of the indicator arm tend normally to maintain the pin 13 in engagement with the block. To disengage the indicator arm from the block the arm is depressed toward the face of the frame when the pin will be out of the slot and free 100 to move toward the notch 15 for throwing the control into inoperative position. The block 17 has another extension 20 provided with a notch 21 for engaging a spring-actuated plunger 22 mounted in the frame 14. 105 The side edges of the extension 20 are beveled, as shown at 23, to automatically displace the spring-actuated plunger 22 as the block approaches the plunger when displaced by the screw 16 in the frame 14. 110

When the block is engaged by the plunger it will be locked and its displacement

in the frame will be prevented. Normally the plunger will be set to lock the block in the intermediate or zero position, but it is self-evident that any other portion of the 5 scale may be selected if so desired. To permit the displacement of the block from its intermediate or locked position, the spring-actuated plunger 22 must be disengaged from the block and for this purpose a push 10 button 24 is provided. The indicator arm, therefore, may be set to the intermediate or predetermined position without the aid of any scale; in consequence, the indicator arm has two positive positions independent 15 of the scale, one of which throws the control out of action, and the other one which permits the firing of the arm at a predetermined vertical angle. Another angle of action of the control may be obtained by the 20 movement of the block 8 along the groove 9 by which it is guided; and the angularity at which the arm will fire will be indicated by a scale provided along the said guiding groove. It will be noted that the arrangement permits the use of a direct scale in lieu 25 of an inverted one as was the case in my patent previously mentioned, it being understood that the block 17 is held in its guideway or groove in the frame 14 at predetermined 30 points or positions for the purposes stated.

The pendulum is suspended to remain vertical, but to prevent the pendulum from acquiring a momentum when the arm is manipulated, the pin 7 is engaged with the 35 slot 25 of the block 8 which limits the swinging arc of the pendulum and the latter will come quickly to rest when the arm is aimed. When the tongue 6 of the pendulum registers with the groove 12 of the block, the trigger 40 may be operated and, therefore, the pendulum 5. By adjusting the position of the block 8 by means of the indicator, the position of the fire arm will have to be altered correspondingly to bring the tongue 6 of the pendulum into register with the recess 12 of the block to permit the operation 45 of the trigger, sear and pendulum.

While I have described the principle of 50 operation, together with the device which I now consider to be the best embodiment thereof, I desire to have it understood that the device shown is merely illustrative and that such changes may be made as are within the scope of the appended claims.

55 I claim:

1. In combination with a fire-arm firing 60 control, including a pendulum, means for gaging the pendulum, means for displacing the pendulum engaging means and having an arm, and means for locking said arm in two predetermined positions, one whereby the control is rendered inoperative, and the other whereby the firing of the arm may take place at a predetermined vertical angle.

65 2. In combination with a fire-arm firing

control, including a pendulum, means for engaging the pendulum, means for displacing the pendulum engaging means and having a swinging arm, a frame for engaging the arm at a predetermined position whereby the control is rendered inoperative, setting means in the frame adapted to be detachably locked to the arm, and locking means for said setting means whereby said arm may be locked in a predetermined position.

3. In combination with a fire-arm firing control, including a pendulum, means for engaging the pendulum, means for displacing the pendulum engaging means, including a swinging arm, a frame wherein said arm is adapted to swing, said arm being depressible to and from the frame, said frame having means for catching the arm in a predetermined position whereby the control is rendered inoperative, setting means adjustable in the frame, said setting means having means for engaging the arm whereby the control may be set, and means for locking the setting means in the frame whereby the arm is locked in a predetermined position.

4. In combination with a fire-arm firing control, including a pendulum, means for engaging the pendulum, means for displacing the pendulum engaging means and having a swinging arm, a frame, said arm being depressible from the frame, said frame having means for catching the arm in a predetermined position whereby the control is rendered inoperative, a setting block adjustable in the frame and having means for engaging the arm, said arm being adapted to be depressed out of engagement with said setting block, and means for locking said setting block to the arm whereby said arm may be locked in a predetermined position.

5. In combination with a fire-arm firing control, including a pendulum, means for engaging the pendulum, means for displacing the pendulum engaging means and having a swinging arm, a frame, a setting block in the frame, a screw for moving the block, said block having an elongated slot, a pin on said swinging arm engaging the slot, said arm being depressible whereby the pin may be disengaged from the setting block and the arm swung independent of same, said frame having means for engaging the pin on the arm at a predetermined position of the arm, and spring-actuated locking means for locking the setting block to the frame whereby the displacement of same by the screw is prevented.

6. In combination with a fire-arm firing control, including a pendulum, means for engaging the pendulum, means for displacing the pendulum engaging means and having a swinging arm, a frame, setting means in the frame, a screw for adjusting the setting means, means for automatically locking the

setting means in a predetermined position, and means for detachably securing the swinging arm to the setting means, said frame having means for locking the arm independent of the setting means after the same has been removed from the setting means, substantially as and for the purpose set forth.

7. In combination with a fire-arm firing control, including a pendulum, means for engaging the pendulum, means for displacing the pendulum engaging means comprising a swinging arm, adjustable setting means adapted to detachably engage the arm, means for locking said arm when disengaged from the setting means, and automatic locking means for engaging said setting means in a predetermined position.

8. In combination with a fire-arm firing control, including a pendulum, means for engaging the pendulum, means for displacing the pendulum engaging means vertically or in a horizontal arc, including an arm, and a multi-part setting means for locking said arm in predetermined positions, including an indicator arm and means to hold the same in operative and in-operative positions, and positions intermediately thereof.

9. In combination with a fire-arm firing control, including a pendulum, means for engaging the pendulum, means for displacing the pendulum engaging means and comprising a swinging arm, a direct scale for indicating the elevation and depression of said swinging arm above or below a predetermined point, and means for automatically locking said arm at predetermined points of said scale.

10. In combination with a fire arm firing control, a pendulum, a block, a trigger, said pendulum being connected to the sear, said block and pendulum having means adapted to register when said pendulum is in a vertical position and whereby said trigger may be operated, said block and pendulum having means for limiting the oscillatory movement of said pendulum, and means for ad-

justing the block substantially as and for the purpose set forth.

11. In combination with a fire arm firing control, a pendulum, a block for limiting the swinging movement of the pendulum, a member controlling the firing of the arm from which the pendulum is suspended, said block normally preventing the movement of the pendulum toward the block, said block and pendulum having means adapted to register when said pendulum is in a substantially vertical position, and means controlling the position of the block, the registration of the means of the pendulum and block permitting the operation of the member controlling the firing of the fire arm.

12. In combination with a fire arm, a member controlling the firing of the arm, a pendulum suspended from said member, a block having means for permitting the movement of the pendulum toward the block by said firing control member when said pendulum is in a substantially vertical position, and means controlling the position of the block substantially as and for the purpose set forth.

13. In combination with a fire-arm a fire control including a pendulum, means for engaging the pendulum, means for displacing the pendulum-engaging means, including a vertically swinging arm mounted exteriorly at one side of the fire-arm, and setting means for locking said arm in predetermined positions and serving to indicate the position of the pendulum engaging means.

14. In combination with a fire-arm a fire control, including a pendulum, means for engaging the pendulum, means for moving the pendulum engaging means comprising a horizontally extending vertically swinging arm, a direct vertical scale coöperative with said arm for indicating the operative position of the pendulum engaging means and means for locking said arm at predetermined points on said scale, as and for the purposes specified.

FRANK DAVID ELY.
